UNITED STATES PATENT OFFICE

JESSE E. HODGES, OF COVINGTON, KENTUCKY.

COLUMN-FORM.

1,300,393.

Specification of Letters Patent. Patented Apr. 15, 1919.

Application filed December 31, 1915. Serial No. 69,613.

To all whom it may concern:

Be it known that I, JESSE E. HODGES, a citizen of the United States of America, and resident of Covington, county of Kenton, State of Kentucky, have invented certain new and useful Improvements in Column-Forms, of which the following is a specification.

This invention relates to improvements in column forms for molding concrete columns and has for an object to produce a sectional metal column form adapted to mold concrete columns of circular cross section and of varying height and diameter.

15 A further object is to produce a sectional sheet metal column form and an improved means of reinforcing it.

These and other objects are attained in the form or mold described in the following 20 specification, and illustrated in the accompanying drawings, in which:

Figure 1 is an elevational view of a mold embodying my invention.

Fig. 2 is a sectional view taken on the line 25 2—2 of Fig. 1.

Fig. 3 is a fragmental sectional view of the clamps for adjustably connecting the ends of the reinforcing bands, shown upon an enlarged scale.

30 Fig. 4 is a fragmental sectional view of a joint between adjacent sheets.

The column form embodying my invention comprises a series of sheets 4 joined together at intervals along their edges, the edges being brought together to circular formation with reinforcing bands 5 spaced apart along the length of the column. The sheets 4 from which the single main sheet which forms the body of the mold, is constructed, preferably extend from top to bottom of the column and are of relatively narrow width. These sheets are provided with aligned apertures 4^a along their edges so that when the apertures of adjacent sheets are brought together the corresponding apertures of the sheets will register with one another. In forming these apertures those in the inner edge 20 of each sheet, which is contacted by the concrete, are formed with an inclined wall 21, the outside of the sheet being preferably provided with a slight annular flange 19. This flange is of such a size that it enters the plain aperture 22 in the outside edge 23 of each sheet. Through 45 these apertures fastening devices such as

bolts 6 having countersunk heads which engage the inclined walled aperture, are passed for the purpose of joining the sheets, the faces of the countersunk heads lying flush with the inside surfaces of the sheets. 60

The form is constructed by joining the sheets at their longitudinal edges, the sheets having previously been curved to a normally curved formation of a radius equal to that of the largest column for which the mold is 65 constructed, to form a cylinder composed of the series of narrow sheets. In order to reinforce the cylinder the reinforcing bands 5 are placed at intervals around it. These bands are adjustable circumferentially so as 70 to reinforce the form for any diameter of column desired. These bands are preferably constructed of metal rod of circular cross section adapted to embrace the curved sheet, and to be adjustably secured at their ends by 75 means of a clamping device 7. This device consists of a coupling 8 having ways 9 and 10 formed therein and crossing one another so that the ends of the rods may cross and lie upon one another within the coupling 8. 80 At the ends of the coupling and extending from one side thereof, journal lugs 11 and 12 are formed, in which eccentric clamp dogs 13 and 14 are journaled, pins 15 and 16 being provided for this purpose. The rod-engaging surfaces of the dogs are eccentric to the pivotal points 15 and 16 and are adapted to engage the ends 17 and 18 of the rods so that the rods will be clamped in position against displacement when the eccentric surfaces are driven into engagement therewith. 85

In setting up the form embodying my invention, the series of narrow sheets 4 from which the form is constructed, are joined together by means of the bolts 6, as shown in Figs. 1 and 2. With the cylindrical form thus constructed, the bands 5 are placed over the joined sheets, adjusted to the proper diameter, and spaced upon the sheets. Of 95 course in order to prevent the slipping of the ends 17 and 18 of each band, from beneath the dogs 13 and 14, the eccentric surfaces of the dogs are driven into clamping engagement therewith after adjusting 100 the bands to the proper diameter. 105

Should it be desired to increase the height of the column, short sections may be added to the main section at its top edges, or two or more sections of standard length may be 110

telescoped with one another until the proper length of mold has been constructed, as shown in Fig. 1.

By previously bending the sheets to a radius equal to that of the largest column diameter of which the mold is capable, the sheets are prevented from buckling during the setting up operations and are also given an initial bend so as to facilitate their further bending when constructing a mold of small diameter. The circumferentially alined apertures of each series aid greatly in the proper adjustment of the form to smaller sizes.

15 To remove the form from the column after it has been molded, it is but necessary to disengage the clamp dogs 13 and 14 from the ends 17 and 18 of the bands and permit the bands to be removed entirely from the 20 curved sheet. If the sheet then adheres to the concrete it may be easily removed by prying it therefrom.

Having thus described my invention, what I claim is:

25 1. A column form comprising a series of sheets secured together adjacent to their edges to form a concrete receiving mold of desired contour, a series of reinforcing bands embracing the mold, and clamps adapted to 30 retain the bands in adjusted positions, said clamps comprising a coupling having inter-

secting ways adapted to receive the ends of the reinforcing band, and an eccentric clamp dog adapted to be driven into engagement with the ends of the band to retain the band 35 in its adjusted position, for any size of mold formed by the assembled sheets.

2. A column form comprising a series of sheets having a series of alined perforations in their edges, means engaging registering 40 perforations of adjacent sheets for securing the sheets together to form a concrete receiving mold, a series of reinforcing bands embracing the mold, and clamps engaging the ends of the bands and adapted to retain 45 the bands in adjusted positions upon the mold, said clamps consisting of a coupling having transverse intersecting ways adapted to receive the ends of the bands in superimposed relation with one another, and clamp 50 dogs having eccentric surfaces pivotally mounted on the coupling adapted to be driven into clamping engagement with the ends of the bands to retain the bands against displacement from their adjusted positions. 55

In testimony whereof, I have hereunto subscribed my name this 24th day of December, 1915:

JESSE E. HODGES.
